Patented Feb. 3, 1925.

UNITED STATES PATENT OFFICE.

JOHN ALEXANDER CAMERON, OF GLASGOW, SCOTLAND.

CALENDAR, DIARY, WRITING OR OTHER PAD.

Application filed June 29, 1923. Serial No. 648,547.

To all whom it may concern:

Be it known that I, JOHN ALEXANDER CAMERON, a subject of the King of Great Britain and Ireland, and a resident of 4 Bluevale Street, Dennistoun, Glasgow, Scotland, have invented certain new and useful Improvements in and Connected with Calendars, Diaries, Writing or Other Pads, of which the following is a specification.

10 My invention relates to improvements in and connected with calendars, diaries, writing or other pads where the sheets are to be permanent and which are suspended and has for its object to so construct such as to facilitate the turning over of the sheets and when turned over each sheet will lie flat against the opposite side of the card-board to which the calendars, diaries, or writing pads are attached, i. e., on the reverse side of card-20 board support to which the unused sheets lie.

In carrying out this invention, I provide a suspender or device of celluloid, or any other fabric or any suitable metal which is suitably pivoted to and lies between a folded card-board forming the support for the calendar, pad or block which lies between the folded card-board which are glued or otherwise fixed together to make a solid support but leaving sufficient room or space at 30 the upper end for the movement of the suspender or device on its pivot. The suspender or device is formed with a suitably shaped head-piece or tab at its inner end provided with an eyelet by which the calendar, diary or other pad is suspended and which, in its normal state, protrudes through a slit in the upper end of the support, and through a corresponding slot in each sheet of the calendar, diary or other pad, the card-board and calendar, diary or the like being connected together by stitching.

In order that my invention may be properly understood and readily carried into effect, I have hereunto appended one sheet 45 of drawings, of which—

Figure 1 is a front view of calendar illustrating my invention.

Figure 2 is a front view in part showing the suspender with tab in the position by 50 which a sheet of the calendar or the like can be turned over.

Figure 3 is an enlarged side view in part of Figure 2 showing pages in act of being turned over to the back.

55 Figure 4 is a front elevation illustrating a modification of my invention.

Figure 5 is a view showing how the diary or the like is connected with the folded card-board support.

Referring to the drawings, 1 is the suspender with head-piece or tab 10, and 2 is the hole in the tab 10 for suspending purposes. 3 is the end of the device 1 which, as will be seen, is cut to a convenient angle so that the point projects beyond the edge of the calendar, diary or other pad when the tab 10 is depressed by the finger which projection 3 acts as a push for returning the tab 10 to its normal position. 4 is the pivot or hinge on which the suspender 1 swivels. 5 are the pages of the calendar, diary or other pad and 6 is the stiff folded card-board which constitutes the back of the calendar, diary or other pad and 9 is the slit of cut-out part in the sheets of the calendar, diary or other pad to enable the sheets to pass over the tab 10. 11 are the stitches by which the calendar, diary or the pad and folded card-board support 6 are connected together as shown.

When it is desired to turn over a leaf or sheet 5, the head-piece or tab 10 is depressed and, in so doing, the suspender or device 1 turns on its pivot 4, the opposite end 3 projects through a slit provided in the side of the support, Figure 2. The sheet 5 is then turned completely over, after which the protruding end 3 of the suspender or device 1 is pushed in and, turning on its pivot 4 in the opposite direction, the head-piece or tab 10 returns to its normal position thus retaining the turned over sheets or pages 5 in their place, Figure 1. The suspender or device 1 is so formed that its movement in either direction is limited whereby it cannot become inactive, i. e. when the tab 10 is pushed down the suspender or device 1 turning on its pivot the upper edge of the projection 3 abuts against the upper end of the card-board back 6, and when the tab 10 is returned to its normal position the opposite or inner corner of the suspender 1 abuts against the inner upper end of the card-board back thus limiting the travel of the device 1 when turned on its pivot and preventing it becoming inoperative.

As an alternative or cheaper arrangement and as shown in Figure 4, I may provide a strip of copper, brass or other wire having a loop or tab 7 formed in the centre thereof and which protrudes beyond the upper end 8 of the support or back, the arms or legs 8 of which lie between the folded card-board

forming the support or card-board back 6 and which are glued together as previously described. This is a fixture and the sheets 5 having the opening 9 in the centre of the upper ends when turned over are not interfered with by the loop or tab 7 and therefore lie snugly at back 6 of the cardboard. The calendar or the like is suspended by the loop or tab 7 and the calendar, diary or other 10 pad and support are stitched together as shown in Figure 5.

I claim:

In calendars, diaries, writing or other pads, the combination of a back having a

hang-up member pivoted adjacent its upper end; and a plurality of folded sheets, each of said sheets having an opening on the line of fold through which one end of said member may extend, the other end of said member being adapted, when the first mentioned end is retracted from said openings, to extend beyond one edge of said sheets.

In testimony whereof I affix my signature in presence of two witnesses.

JOHN ALEXANDER CAMERON.

Witnesses:

JOHN LIDDLE,

JOHN TRAIN LIDDLE.
